UNITED STATES PATENT OFFICE.

JACOB B. HOOVER, OF COLUMBUS, OHIO.

Diestock.

1,320,756.

Specification of Letters Patent.

Patented Nov. 4, 1919.

Application filed April 20, 1917. Serial No. 163,397.

To all whom it may concern:

Be it known that I, JACOB B. HOOVER, a citizen of the United States, and a resident of Columbus, county of Franklin, and State 5 of Ohio, have invented a new and useful Improvement in Diestocks, of which the following is a specification, the principle of the invention being herein explained and the best mode in which I have contemplated 10 applying that principle, so as to distinguish it from other inventions.

The present invention, relating as indicated to die stocks, is more particularly concerned with the construction of a die head or 15 holder, in which the die itself may be accurately and perfectly adjusted and held in such a way that the thread-cutting portions of the die form a perfect circle and produces a true circular threaded member. 20 Another object of the invention is the provision of a simple and convenient adjustment for a die in a holder and also an equally convenient removal of the collet which cooperates with the portions of the die to 25 maintain the member being threaded in position. To the accomplishment of the foregoing and related ends, said invention, then, consists of the means hereinafter fully described and particularly pointed out in the 30 claims.

The annexed drawing and the following description set forth in detail certain mechanism embodying the invention, such disclosed means constituting, however, but one 35 of various mechanical forms in which the principle of the invention may be used.

In said annexed drawings:

Figure 1 is a front elevation showing a die stock constructed in accordance with 40 my invention; Fig. 2 is a vertical longitudinal section through the die holder and die; and Fig. 3 is a transverse central section on the line 3—3, Fig. 2, showing the collet.

In Fig. 1 there is shown a die holder 1 having the usual enlarged, circularly apertured center and oppositely extending handles 2. The central portion is split along a vertical line and is provided with two upwardly extending lugs 3. These lugs 3 are provided with aligned apertures which are threaded to receive an adjusting screw 4 for contracting or expanding the size of the die holder 1. For convenience of operation the adjusting 55 screw 4 is provided with a transverse aper-

ture 5 in its head, in which may be received an adjusting lever 6.

The die 15 which is used in the holder 1 is of the type known as a single one-piece die, which is split transversely and is provided with oppositely beveled corners 7 and 8 at its ends. These oppositely beveled corners 7 and 8 are so formed with respect to each other that a right angle is produced thereby. Mounted at one side of the upwardly extending lugs 3 is a boss 9, which is provided with an aperture directed at right angles to the plane of the right-hand corner 7 (as seen in Fig. 1). In this threaded aperture in the boss 9 is mounted a similarly threaded adjusting pin 10, which is provided with a flat right-angled end adapted to contact the surface of the corner 7. Upon inward movement the pin 10 is adapted to force the die 15 circumferentially 70 in the holder until the other corner 8 of the die engages squarely against the side of the pin 10. Thereafter further movement of the adjusting pin opens the die and also forces the same into contact with the die 75 holder. To adjust the die to any desired size the die holder is first opened slightly by adjustment of the screw 4, and the die is then expanded by adjustment of the pin 10. When the die has been expanded the amount 80 desired the holder is clamped tightly upon the die by further adjustment of the screw 4.

I have found that by adjusting first the die to the holder by circumferential movement and expansion of the die, and then by adjusting the holder to the die there is no chance for breakage of the die at its weakened portion opposite to the transverse slit therethrough, and furthermore the threaded surfaces of the die are so positioned that 95 they constitute a perfect circle and will cut perfectly formed threads on the stock.

Referring now to Fig. 3, there is shown in the back of the die holder 1 a plate 16 provided with an extension in the form of a 100 sleeve 17, in which there is removably mounted a collet 18. The collet 18 is formed with a flange 19 resting against the end of the sleeve, and is held in position by means of a set screw 20 entering a recess 21 in the 105 collet, thus permitting the use of collets of different inner size in the same sleeve. On the rear face of the die holder there is formed an interiorly projecting flange 22, against which the plate 16 is adapted to rest 110

when the sleeve is engaged in the die holder, and a screw 23 may be used to engage the two flanges with each other to maintain the sleeve in position.

5 The simplicity of construction and convenience of adjustment of the several parts of my improved die stock will be readily appreciated and it will be obvious that the invention is not limited to use in hand tools 10 alone, but may be equally useful when applied to automatic screw machines.

Other modes of applying the principle of my invention may be employed instead of the one explained, change being made as 15 regards the mechanism herein disclosed, provided the means stated by and of the following claims or the equivalent of such stated means be employed.

I therefore particularly point out and 20 distinctly claim as my invention:—

1. In a die, the combination of a split, 25 adjustable die head, a split die member fitting within said head and circumferentially movable therein, the ends of said die member being beveled outwardly, and an adjusting pin mounted in said head, said pin having a right angled inner end and being mounted with such end bearing against one beveled end of said die, said pin being 30 adapted, when moved inwardly, to initially move said die circumferentially and to expand the same upon contact of such other beveled end of said die against the sides of said pin.

35 2. In a die, the combination of a split, ad-

justable die head, a split die member fitting within said head and circumferentially movable therein, the ends of said die member being beveled outwardly, and an adjusting pin mounted in said head at an angle to a 40 radial line therethrough, the inner end of said pin engaging laterally against one beveled end of said die and forming a bearing therefor, and said pin engaging against the other end of said die and being adapted, 45 upon inward movement, to expand the same.

3. In a die the combination of a split adjustable die head, a split die member within 50 said head and having outwardly beveled ends, an adjusting screw mounted in said head and adapted to bear against one of such beveled ends, the other beveled end being adapted to contact with the sides of said screw, movement of said screw being adapted to expand said die member circumferentially in said head.

4. In a die the combination of a die head split at one point, an adjusting screw mounted in said head and adapted to adjust the same, a die member split at one point 60 mounted in said head, an adjusting screw mounted in said head and adapted to expand said die member circumferentially, said die head and member being split upon radial lines, spaced at an acute angle to 65 each other, so that said member and said head will remain approximately concentric throughout their adjusted positions.

Signed by me this 14th day of April, 1917.
JACOB B. HOOVER.
